(57) **CLAIM**

The ornamental design for a control panel, substantially as shown and described.

DESCRIPTION

FIG. 1 is a front perspective view of a design for a control panel, which may be used in a security system, a home automation system, etc.;

FIG. 2 is a front view of the embodiment of the design for the control panel shown in FIG. 1;

FIG. 3 is a first side view of the embodiment of the design for the control panel shown in FIG. 1;

FIG. 4 is a second side view of the embodiment of the design for the control panel shown in FIG. 1;

FIG. 5 is a top view of the embodiment of the design for the control panel shown in FIG. 1;

FIG. 6 is a bottom view of the embodiment of the design for the control panel shown in FIG. 1; and,

FIG. 7 is a rear view of the embodiment of the design for the control panel shown in FIG. 1.

The dash-dot broken line showing of the environment is for illustrative purpose only and forms no part of the claimed design. The dot-dot broken lines define the bounds of the claimed design and form no part thereof.
